UNITED STATES PATENT OFFICE

HOMER L. WORBOIS, OF LANSING, MICHIGAN, ASSIGNOR TO GENERAL MOTORS CORPORATION, OF DETROIT, MICHIGAN, A CORPORATION OF DELAWARE

CRANK-CASE-VENTILATING SYSTEM FOR INTERNAL-COMBUSTION ENGINES

Application filed July 19, 1926. Serial No. 123,372.

This invention relates to crankcase ventilating systems for internal combustion engines. Such systems are designed to pass considerable volumes of air through the crankcase to effect evaporation of diluents such as fuel and water from the lubricating oil to prolong its life. In the winter months it is frequently the case that evaporation will not take place in any great measure unless heat is applied to the crankcase contents. My system is designed to produce a considerable flow of air through the crankcase and to provide the necessary heat even in the coldest weather, and is also of such simple construction as to be suitable for use in production on low priced cars.

According to my invention air is supplied to the carburetor and to the crankcase from a hot air stove of conventional design. Successively, preferably derived from the engine intake, is employed to withdraw the mixture of air and vapors from the crankcase. If desired, the stove may be provided with an air cleaner of the type shown in the application of Charles F. Kettering, Serial No. 71,367, filed Nov. 25, 1925, so that there is no possibility of dirt being drawn into the crankcase or the carburetor. I have also provided means for adjusting the amount of air drawn through the crankcase in accordance with varying conditions of temperature and service. This may take the form of a simple type of valve at the crankcase outlet.

In the drawings:

Figure 1 is a side elevation of an automobile engine with my system applied thereto. Figure 2 is a view of the opposite side of the engine from that shown in Figure 1. Figure 3 is an end elevation of the engine with parts broken away and sectioned to better show my ventilating system.

Figure 4 is a sectional view through the combined air heater and cleaner.

I have indicated at 2 a conventional type of automobile engine having a crankcase 4, carburetor 6, intake manifold 8, and oil filler tube 10. 12 indicates a portion of the exhaust conduit upon which is mounted a combined air heater and cleaner 14 of the type disclosed in the application of Charles F.

Kettering, above referred to. This device is shown in detail in Figure 4 and consists of a cylinder 16 surrounding the exhaust conduit and having one end closed by cap 18 and the other end by cap 20 provided with a depending flange 22 which serves to cover the openings 24 formed in the upper end of the cylinder 16. As shown in the drawings the combined cleaner and heater extends in a generally rearward direction and is exposed to the blast from the usual cooling fan indicated at 26. With this arrangement the hood 22 shields the openings 24 against the entrance of dust, the dust particles because of their greater inertia being carried past the hood.

Clean air entering the cylinder 16 through the apertures 24 becomes heated by contact with the hot walls of the exhaust conduit and a portion of the heated air passes through conduit 28 to the air intake of carburetor 6. Another portion of the heated air is led by conduit 30 to the crankcase 4 where it assists in evaporation of diluents.

The oil filler tube 10 is of special construction in that it is provided with a tubular liner 32 secured to the top of the tube in any preferred manner as by welding to the inturned flange 34 provided at the top of the tube. The annular chamber between the liner 32 and the tube 10 communicates with the air intake conduit 28 leading to the carburetor through a conduit 36 secured to the side of the filler tube and to the intake conduit as clearly shown in Figure 2. This method of connecting the conduit 36 with the filler tube insures that oil will not pass into the conduit when the engine oil supply is being renewed. The tube is provided with a suitable closure cap indicated at 40.

With the construction described clean heated air will pass directly to the carburetor through conduit 28 and will also pass through conduit 30 into the crankcase and thence with its crankcase vapor content through the annular space between the tube 10 and liner 32 through conduit 36 into the conduit 28 adjacent the carburetor. I have regarded it as desirable to provide means to vary the volume of air passing through the crankcase and therefore illustrate a valve 100

42 controlled by suitable connections 44 which
may be raised or lowered to increase or de-
crease the volume of air passing through the
crankcase. This valve may be controlled
5 from the dash or if desired may be thermo-
statically operated.

I claim:

1. The combination of an internal combus-
tion engine having a carburetor, a crankcase,
10 an exhaust conduit, a hot air stove mounted
on the conduit, means for conducting hot air
from the stove to the carburetor, means for
conducting hot air from the stove to the
crankcase, means for withdrawing vapors
15 from the crankcase into the engine intake,
said vapors being replaced by hot air from
the stove.

2. The combination of an internal combus-
tion engine having a carburetor, a crankcase,
20 an exhaust conduit, a hot air stove mounted
on said conduit, means for conducting hot air
from the stove to the carburetor, means for
conducting hot air from the stove to the
crankcase, means for applying intake suction
25 to the crankcase to withdraw vapors there-
from, and adjustable means for varying the
amount of air drawn through the crankcase.

In testimony whereof I affix my signature.
HOMER L. WORBOIS.
